PUMP CONSTRUCTION

Eugene S. Witchger, Grosse Pointe, Mich., assignor to Eaton Manufacturing Company, Cleveland, Ohio, a corporation of Ohio

Application December 10, 1942, Serial No. 468,500

5 Claims. (Cl. 103—126)

1

This invention relates to pumps in general, and, more particularly, concerns a pump construction mountable directly upon an internal combustion engine block without a separate pump body and in communication with ports in the engine block.

It has been suggested heretofore to incorporate engine pump intake and discharge openings in the engine block with a view to reduction in the total cost of the engine, and advancement of the art in general. Such suggestions insofar as applicant is aware, have been limited to intake and discharge ports of a size and shape normally able to accommodate the timing for which the pump was designed, and, also any slight coring inaccuracies that might occur in the block casting operation, and which would otherwise render the block worthless for a pump construction, such as the present, which is critical in its porting arrangement, by providing a separate accurate porting plate insert held in predetermined relation with respect to the rotor pumping elements. However, the present invention advances the state of the art further and proposes to dispense with a cored and machined pump pocket cast integrally into a boss on the engine block; and also, the separate porting plate insert by the use of primary intake and discharge ports having elongated openings at the outer ends thereof in an engine block boss, and which are inadequate to accommodate sufficient working fluid for a complete pumping cycle, by providing secondary distributing or balancing ports in a pump cover element that are disposed outwardly in timed relation to the pumping elements which overlie the elongated but inadequate primary intake and discharge ports. When the primary intake and/or discharge ports are referred to hereinafter as "inadequate" it will be understood to mean inadequate to supply sufficient working fluid for all the pump cavities during a complete pumping cycle, as aforementioned.

The present invention proposes the use of a highly efficient pump construction that has recently found much favor in numerous pumping applications, which, although rather critical in the porting arrangement therefor, has increased efficiency over the other known pump constructions, particularly at low speeds. Such a pump mechanism is described in the Hill Patent No. 1,682,563, issued August 8, 1928, to which attention is directed. In a rotor pump such as described in the present application having a change in volume through substantially its entire cycle, the intake and discharge cavities of said mechanism are exposed to the intake and discharge ports in the engine block, in this instance,

2

through a materially lesser portion of the cycle. The change in volume of the cavities not exposed to the intake and discharge ports in the engine block being communicated through the cavities exposed to the intake and discharge by the balancing ports in the pump cover element.

Accordingly, among the objects of the present invention are the provision of a pump construction mountable directly upon a pump boss or pad cast integrally with and incidental to operations upon the engine block and in which boss intake and discharge openings inadequate to accommodate sufficient working fluid for a full pumping cycle are disposed, and over which a pair of rotor pumping elements are positioned to be housed by a pump cover element containing secondary distributing or balancing ports therein in timed communication with the cavities of the pumping elements through the entire pumping cycle; the provision in a pump construction as described of means for intaking the working fluid of the pump from an inadequate primary intake port directly to the pumping elements and passing it through secondary distributing or balancing ports disposed in timed relation to the pumping elements and discharging it back to an inadequate discharge port on the same end of the pumping elements as the intake port; the provision in a pump construction as described in which inadequate primary intake and discharge ports are disposed directly adjacent one end of the pumping elements, and secondary distributing porting balances the pressure through the entire pumping cycle upon the opposite end of the pumping elements; the provision in a pump construction as described above in which said secondary balancing ports are accurately disposed in timed relation adjacent to the outer end of the pumping elements in a pump cover element; and the provision in a pump construction as described in which the velocity of the working fluid confined in the cavities of the pumping elements is in excess of the velocity required to fill these cavities whereby to carry enough excess working fluid through the pumping elements, at the position to which they are exposed to the inadequate primary ports in the engine block, to accommodate the change in volume in the rotor elements that are not exposed to said ports, but only balanced by the large secondary porting in the cover element.

Further and other objects and advantages of the present invention reside in the novel combination and arrangement of parts, about to be described, when considered in conjunction with the drawing forming a part of this specification and

pointed out with particularity in the appended claims.

In the drawing like reference characters denote corresponding parts throughout the several views, and in which:

Fig. 1 is a vertical sectional view through a portion of an engine block illustrating one form of this invention; and

Fig. 2 is an elevational view of a pump boss cast integral with the engine block of Fig. 1, illustrating the small elongated primary intake and discharge ports cast therein, and taken on the line 2—2 thereof; and

Fig. 3 is an elevational view taken facing the pump cover member with the pumping elements therein, on the line 3—3 of Fig. 1; and

Fig. 4 is a further elevational view similar to Fig. 3 with the pumping elements removed revealing the accurately formed and indexed secondary balancing ports disposed in timed relation to the pumping elements; and

Fig. 5 is a horizontal sectional view through the pump structure illustrating the substantially continuous registration, throughout the pumping cycle, of the elongated intake port with the distributing ports upon the opposite end of the rotor elements, and taken substantially on the broken section line 5—5 of Fig. 3.

Now having reference to the drawing and particularly Fig. 1, there is shown an engine block, generally designated 10, which has an oil sump or crankcase 11 at the lower portion thereof. Projecting from an end wall of the block, conveniently located adjacent the end of a driving means therein, is a boss or pad 12 that is cast and cored out integral with the engine block and incidental to operations performed thereon. From the face of the boss or pad 12 intake and discharge passages 14 and 15, respectively, are drilled inwardly at any suitable angle thereto along with the other operations performed upon the block to provide channels for the working fluid of the pump. In communication with the passage or line 14 is a suction pipe 17 secured thereto by means of a fitting 18 and having a filter screen 19 over the lower pipe end to strain oil inducted thereinto. The discharge passage 15 is communicated with oil galley 20 which conducts lubricant under pressure to any desired point.

In order to connect the pump mechanism with a driving means in the engine, a cam shaft 23 is journalled adjacent thereto in a pocket formed in the block and from the inner end of the pocket an opening is formed through the outer wall of the block at substantially the central portion of the boss or pad 12 for reception of a reduced end portion of the cam shaft 23 which serves as the drive shaft 25 for the pumping elements. Press fitted or otherwise suitably keyed to the drive shaft 25 a pumping element, in this case the inner male rotor member 26, is secured. Surrounding the male rotor 26 is an outer female rotor 27. It will be apparent that the female rotor 27 has one more internal cavity than the number of generated teeth on the male rotor 26 such as the pump construction described in the mentioned Hill patent to which reference may be had for a more complete description. Disposed adjacent the outer end of the rotor elements is a pump cover element 30 having a gasket sealing means 31 pressed to the boss 12 and secured in predetermined position by any suitable fastening means 32.

Now having reference to Figs. 2, 3 and 4, there

is shown in the cover member 30, which receives the outer toothed female rotor 27 with a running fit, a pair of secondary distributing ports 34 and 35, being the intake and discharge, respectively, 5 integral with the cover member and disposed in accurate timed relation with respect to the pumping elements 26, 27 and the said inadequate primary intake and discharge openings 36 and 37. In order to accommodate some inaccuracy and other slight coring defects which may occur incidental to forming the engine block 10, as aforementioned, the outer ends of the intake and discharge passages 14 and 15 are cored out, or otherwise formed, to provide small elongated ported openings 36 and 37 communicated with the said passages, respectively, as best shown in Fig. 2. While the secondary distributing porting 34 and 35 is in this instance of substantially crescent shape it will be obvious the shape of the ports 10 may be varied according to the requirements desired in the finished pump to meet certain operating conditions, and the specific form shown is merely for purposes of illustrating the general principle. Additionally, the principal teaching of 15 the invention is equally applicable to comparable pump constructions other than rotor pumps as hereinbefore described and may be employed on vane type pumps, or other rotary pumps having a change in volume through substantially the entire pump cycle, with similar surrounding structural limitations. The secondary porting 34 and 35 in the inner face of the outer end of the cover member 30 will be hereinafter referred to generally as "distributing" porting in the specification and claims, since these ports are not in communication with the primary intake and discharge passages except through the pumping elements.

One of the principal features of this invention 20 is the provision in a rotary type pump of the character described, in which a volume change is effected through most of its cycle, to have the ports which are inadequate to accommodate sufficient working fluid for a complete pumping 25 cycle communicate with the pumping chamber through the same portion of the cycle; and this is accomplished in the present instance by omission of a separate porting plate insert and communicating the pump rotors directly with said 30 inadequate ports in the engine block on one end and on the other opposite end of the rotors by means of said secondary or distributing ports, which balance the pressure through substantially the entire pump cycle, and are disposed in timed 35 relation to the rotor elements housed in the pump cover member.

To illustrate the principle of intaking and discharging the working fluid of the pump through 40 inadequate port means which are balanced by distributing ports formed in a pump cover element that is disposed in timed relation to the pumping elements, there is shown in Fig. 5 a horizontal sectional view through the pump, as on the broken line 5—5 of Fig. 3. From this view 45 it will be seen that, to have a continuous efficient discharge from the pump it is essential that the velocity of the fluid confined between the cavities in the pumping element as at 40 be in excess of the velocity required to fill that volume as it is necessary to move enough excess fluid through 50 the pumping elements at the time during which each cavity is exposed to the inadequate primary ports 36 and 37 to compensate for the change in volume of the cavities in the pumping elements during the time they are not exposed to

said inadequate primary ports 36 and 37 in the block but only balanced by the secondary distributing porting 34 and 35 in the cover element 30. Investigation and reflection will reveal this to be necessarily true and essential since without such accurate timing of the secondary distributing ports at one end of the rotors with respect to the inadequate intake and discharge ports at the other end of the rotors, would result in a condition where fluid would be inducted into the 10 cavities between the rotors, moved partially around a portion of the cycle of the rotors by the rotation thereof, and then have no place to relieve or discharge the pressure built up in the fluid. A rotary pump having ports inadequate to fill the rotor spaces throughout the entire 15 pump cycle without adequate balancing ports would be inoperative because the fluid confined in the rotor spaces not exposed to the ports would be raised to an excessive pressure, and the rotor spaces not exposed to the intake would cavitate, resulting in an extremely inefficient pumping cycle. Accordingly in the claims, where the secondary or distributing porting is referred to as 20 "balancing" or "compensating" cavities in the pumping elements not in communication with the inadequate intake and/or discharge ports, it will be understood to mean that changes in volume of the working fluid in these cavities is accommodated or effected through communication with the adjacent distributing porting.

From the foregoing disclosures it will now be apparent there has been provided a novel pump construction directly mountable upon an engine block which has been operated upon incidental to the usual casting and machining operations thereof and may result in inadequate intake and discharge ports therein to be communicated with one end of a set of pumping elements that are pressure balanced upon the opposite end thereof by accurate distributing ports readily incorporated in a pump cover element, thereby eliminating a separate porting plate insert, and which embodies among other things the objects and advantages of the invention first enumerated. It is to be understood, however, the specific form of the invention disclosed is merely for purposes of illustration, as many other formal modifications will now be suggested to those skilled in the art and in actual practice, which will come within the spirit and substance of the broad invention as defined by the scope of the following claims.

What I claim is:

1. The combination in a rotary pumping mechanism of the character described having a change in volume of the working fluid effective through a substantial portion of a pumping cycle; of housing means forming a pumping chamber, a pair of rotary pumping elements in said chamber which cooperate to define hollow cavities between them that expand and contract to produce suction and compression phases during rotation thereof, said housing means having intake and discharge ports located therein adjacent one end of said pumping elements and of inadequate length circularly of said elements to accommodate sufficient working fluid for a complete pumping cycle thereof with relation to the respective pumping cavities adjacent thereto, said housing means being provided with distributing porting 70 therein adjacent the opposite end of said pumping elements, and said distributing porting being of sufficient length circularly of said elements and disposed in accurately timed relation to the cavities in said pumping elements to balance

pressures developed in the working fluid through the same portion of the pumping cycle as first mentioned, whereby a continuous efficient discharge is effected during that portion of the pump cycle in which a portion of the pumping cavities communicated with said inadequate intake and discharge ports are compensated for by the change in volume of the working fluid in other pumping cavities communicated therewith only through the distributing porting.

2. The combination in a rotary pumping mechanism of the character described having a change in volume of the working fluid effective through a substantial portion of a pumping cycle and including intake and discharge ports communicated with the pumping mechanism through the same portion of the cycle; of housing means forming a pumping chamber, pumping elements in said chamber which cooperate to define hollow cavities therebetween that expand and contract in volume to produce suction and compression phases during rotation thereof, said housing means having an intake and a discharge port located adjacent one end of said pumping elements which ports are of inadequate length circularly of said elements to accommodate sufficient working fluid for a complete pumping cycle thereof with relation to the respective pumping cavities, said housing means being provided 25 with distributing porting therein at the opposite end of said pumping elements, and said distributing porting being of a sufficient length circularly of said element as to adopt said distributing porting to accommodate changes in pressure in the volume of the working fluid through substantially an entire pumping cycle on the opposite end of said pumping elements to effect a continuous efficient discharge through the pumping elements from the first side thereof.

3. In a rotary pumping mechanism of the character described having a change in volume of the working fluid effective through a substantial portion of a pumping cycle and including intake and discharge ports communicated with the pumping mechanism through the same portion of the cycle; the combination of housing means forming a pumping chamber, pumping elements in said chamber which define hollow cavities between them that expand and contract in volume to produce suction and compression phases during rotation thereof, said housing means having an intake and a discharge port therein opening onto one end of said pumping elements, each of said ports being of inadequate length circularly of said elements to accommodate sufficient working fluid for a complete pumping cycle of said pumping elements with relation to the respective pumping cavities, said housing means being provided with distributing porting therein opening onto the opposite end of said pumping elements, the distributing porting indirectly communicated through said expanding cavities between the pumping elements with the inadequate intake port and through said contracting cavities between the pumping elements with the inadequate discharge port on the opposite end thereof, and said distributing portings extending angularly of said elements beyond said intake and discharge ports and being so constructed and arranged that the velocity of the working fluid in the pumping cavities connecting said inadequate intake port with its corresponding distributor port is in excess of that required to provide only the volume necessary to fill the pumping cavities in communication with the intake port, whereby to compensate

for a change in volume of the working fluid in other pumping cavities not exposed to said intake port but only balanced by said distributing porting.

4. A rotary pumping mechanism for liquids comprising housing means forming a pumping chamber therein and rotary pumping means in said chamber, said pumping means exerting a suction effect angularly of said chamber over substantially 180° thereof and exerting a pressure effect over substantially the remaining 180° thereof, said housing means having an intake port and a discharge port opening onto one end of said chamber serving as the sole means for introducing and discharging liquid to and from said chamber, said ports being so materially smaller in angular extent as compared to the corresponding suction and discharge effects of said pumping mechanism as to be inadequate for complete functioning of said effects, the opposite end of said chamber having a pair of blind ports formed therein, one of said blind ports extending over approximately the angular extent of said suction effect and the other of said blind ports extending over approximately the angular extent of said discharge effect, whereby to enable said pumping mechanism to exert suction and discharge effects over approximately the complete angular extent thereof regardless of the angular inadequacies of said suction and discharge ports by cross-flow through said pumping means.

5. A rotary pumping mechanism of the char-

acter described comprising means forming a pumping chamber and a housing therefor, rotary pumping means in said housing, said pumping means exerting a discharge and a suction effect each over a material angular extent of said chamber with respect to the center of said chamber, one end of said chamber having an intake and a discharge port opening thereinto and onto said pumping means, each of said ports being of an angular extent insufficient to accommodate the full angular extent of said discharge and suction effects and forming the sole means for introducing and discharging liquid to and from said chamber, and the opposite end of said chamber having a pair of blind ports therein opening onto said pumping means, one of the last-mentioned ports being of an angular extent substantially equal to said suction effect of said pumping means and being so located with respect thereto as to enable said suction effect to be completely satisfied by flow axially through said pumping means from said suction port and through said one of said blind ports, and the other of said last-mentioned ports being of an angular extent substantially equal to said discharge effect of said pumping means and being so located with respect thereto as to enable said discharge effect to be completely satisfied by flow axially through said pumping means from said other of said blind ports to said discharge port.
